UNITED STATES PATENT OFFICE.

FREDERICK W. MEYERS, OF CHICAGO, ILLINOIS.

ROPE CLAMP.

Application filed March 13, 1925. Serial No. 15,242.

To all whom it may concern:

Be it known that I, FREDERICK W. MEYERS, a citizen of the United States, residing at Chicago, in the county of Cook and State 5 of Illinois, have invented new and useful Improvements in Rope Clamps, of which the following is a specification.

The present invention relates to what are commonly known in the art as rope clamps 10 and relates particularly to a device possessing a gripping member operable in either direction.

Among the objects of the invention are the following:—

15 The provision of an unique rope gripping member having a novel movable grip face in association with a permanently affixed portion;

20 An unique locking member adapted to retard movement of the cable or rope gripped thereby and so disposed that it may be made to operate in one of two directions as desired;

25 An unique association between the body member and a movable clamp member of an improved configuration and disposed upon said body in such a manner that it may be used equally well in a plurality of directions;

30 A simplified construction for a rope clamp whereby the number of parts is reduced and their manufacture rendered a simple matter.

These, and such other objects as may hereinafter appear, are attained by the novel 35 construction of the several elements which constitute the device, the combination of said elements one with another, and their arrangement, all of which is fully disclosed in the accompanying single sheet of drawing in which other embodiments of the invention 40 are illustrated.

In the drawing:—

Figure 1 is a side elevation of one embodiment of the invention.

45 Figure 2 is a front elevation of the same embodiment of the invention disclosing the gripping action of the member in one direction in full lines, and the gripping action thereof in the other direction in dotted lines.

50 Figure 3 is a side elevation of a second embodiment of the invention; and

Figure 4 is a side elevation of a device comprising a wall bracket or plate mounting two of the clamp members.

60 Like reference characters are used to des-

ignate similar parts in the drawing and in the description which follows.

Reference should be had to Figures 1 and 2. The rope holding member comprises a body 10 having a threaded shank 11 adapted to be secured to a wall or other member to which the device is to be anchored. The upper end of the body 10 comprises a hook portion 12, the material of said hook portion being so disposed that the clamp member now to be described will fall in a line parallel with the shank 11.

At the lower end of the body 10 and adjacent that portion thereof which is curved preliminary to forming the threaded shank 70 11 is an aperture 13 adapted to receive a rivet 14 having a head 15. The body of rivet 14 is of greater diameter than the aperture 13 and said rivet 14 is held upon the body 10 by a constricted section 16 inserted 75 into aperture 13 and riveted at 17 in a manner common to many arts.

Disposed upon the rivet 14 is a movable member 18 having an aperture 19 slightly larger than the body portion of rivet 14. 80 Member 18 is always placed in position upon the rivet 14 before said rivet 14 is secured to body 10 in the manner described in the preceding paragraph.

Movable member 18 comprises a body 85 somewhat diamond shaped. Its sides 20 are smooth and converge at a point below the aperture 19. Its upper sides 21 are corrugated to increase their gripping surface, such corrugations being transverse to the 90 strand of rope adapted to be gripped thereby. Sides 21 converge at a point closely adjacent to the hook 12, and the member 18 should be of such a dimension that it just clears the material of hook 12. Under these 95 circumstances, member 18 is adapted to secure a rope, designated 22 in Figure 2 as such rope passes beneath the hook 12.

One of the sides 21 will engage rope 22 to prevent movement of rope 22 in a direction which would bring the point of intersection between the sides 21 beneath the hook 12. The device as described possesses an adaptability to receive ropes of several dimensions, and may be operated to prevent 105 the rope 22 from being pulled in either direction as shown in Figure 2.

To release the rope 22 it is only necessary to pull the loose end so that the clamp 18 is moved in the direction of the pull, and 110 while loosened, to move said member 18 a

sufficient distance to clear its engagement from the rope 22.

A second form of the device is shown in Figure 3. A bent wire member 30 comprises an eyelet portion 31, a hook 32, a rivet 34, and a movable member 38. The eyelet 31 serves to provide means for attaching the rope clamp to an anchor, while the rivet 34 may be of the same diameter throughout, 10 said rivet 34 being adapted to be seated in the apertures in the material of body 30 at opposite sides of the movable member 38. The construction of the member 38 is identical with that of 18 previously described, 15 and its manner of operation is the same.

The third form of the invention is shown in Figure 4 wherein a bracket or wall plate 40 is shown secured by nails or screws 41 to a wall or other member suitable for 20 anchoring the device. The bracket 40 comprises material bent at right angles to that portion through which the fastening members 41 are inserted and terminating in hook portions 42 substantially identical with the 25 hook 12 shown in Figures 1 and 2.

Rivet members 44, corresponding to rivet 14, are disposed at opposite sides of bracket 40 to hold in position movable grip members 48, such grip members identical in structure and operation with the grip member 18 disclosed in Figures 1 and 2.

It is not my intention to be limited to the precise structures shown, but to consider as my invention all structures falling within the scope of the claim hereto appended.

I claim:

A rope clamp comprising a body having means for attachment to an anchoring object and an offset portion forming a cleat, 40 and a substantially diamond shaped member pivoted at one end and seated in said offset portion with its other end in juxtaposition to said cleat, said member and the rope engaging portion of said cleat being in 45 alignment with said body, and said last mentioned end having contiguous edges knurled to securely engage a rope intermediate said member and said cleat.

FREDERICK W. MEYERS.
